SOUND RECORDING TAPE REEL

John E. Cahill, Birchwood, Minn., assignor to Minnesota Mining & Manufacturing Company, St. Paul, Minn., a corporation of Delaware

Application April 4, 1955, Serial No. 35,331

Term of patent 14 years

(Cl. D26—14)

Figure 1 is an elevational view of one side of a sound recording tape reel, showing my new design, the opposite side having substantially the same appearance;

Figure 2 is an end elevational view of the reel; and

Figure 3 is a sectional view along the line 3—3 of Figure 1.

The dominant features of my new design are shown in solid lines in the drawing.

I claim:

The ornamental design for a sound recording tape reel, as shown and described.
